UNITED STATES PATENT OFFICE.

JEAN JACQUES, OF PHILADELPHIA, PENNSYLVANIA, ASSIGNOR OF ONE-HALF TO
ADOLPH W. OSWALD, OF PHILADELPHIA, PENNSYLVANIA.

CLOSURE.

Application filed February 5, 1926. Serial No. 86,133.

This invention relates to closures for the intakes of storage or other receptacles such for example as gasoline tanks, oil reservoirs or radiator tanks of automobiles.

5 The objects of my invention are to enable quick and ready access to the receptacle openings for filling, and to secure this advantage in a closure which is easy to operate, capable of normally maintaining a good 10 fluid tight seal in preventing evaporation of the receptacle contents; and which, on the whole, is capable of very economic manufacture from sheet metal die stampings.

In the drawings Fig. I is a perspective 15 view of a closure conveniently embodying my invention.

Fig. II is a similar view showing the control rotor turned to open position for filling of the receptacle.

20 Fig. III is a longitudinal sectional view of the device.

Fig. IV is a cross section taken as indicated by the arrows IV—IV in Fig. III; and

25 Figs. V, VI, VII and VIII are perspective views of the parts which collectively constitute the device.

As herein shown, the closure comprises a casing 10 and a rotor 11 which is accommodated in the horizontal cylindric portion 12 of the casing to control communication between aligned diametrical upper and lower ports 13, 14 therethrough. At the bottom, the casing 10 has an annular base flange portion 15 which is internally threaded for application to the inlet neck of the receptacle whereof a portion is shown at N in Figs. III and IV, and may be equipped with one or more set screws 16 for security of the device against subsequent displacement and illicit removal. The body portion 17 of the rotor 11 is semi-cylindric in configuration, its circumferential dimension approximating a half circle in extent as will be best seen from Fig. VIII, and it has an opening 18 adapted for registry with the upper port 13 of the casing 10 as well as a cut out at 19 to clear the lower port 14 when said rotor is in open position. The extent of movement 40 of the rotor 11 is limited by engagement of offset projecting grasp lugs 20—21 of its circular end 22 (Figs. I, II and VII) respectively with stops 23—24 on the casing 10. When the rotor 11 is in closed position, 45 a segmental arcuate plate 25 forming a part

thereof and which is rounded in conformity with the exterior curvature of the cylindric rotor casing 12, serves as a cover over the upper port 13.

In operation of the device, turning of the 60 rotor 11 clockwise from the position of Fig. I with the aid of the grasp lugs 20, 21 and as far as permitted by the stop 24, will result in the shifting of the segmental cover plate 25 from over the upper port 13 of the casing 10 and simultaneous registry of the rotor opening 18 with said port as shown in Fig. II. At the same time, the cut out 19, of the rotor 11 is of course brought into coincidence with the lower port 14 of the casing 10 so that communication is had through the device for filling or inspection of the receptacle with which it is used. Turning of the rotor 11 counterclockwise from the position of Fig. II will obviously result in 70 restoration of the device to closed position with the imperforate portion of the rotor body 17 closing the lower port 14 of the casing 10, and the segmental cover plate 25 overlying the upper port 13 as in Fig. IV. 80

The operation of the device being now well understood, I will next proceed to describe the manner in which it can be conveniently and inexpensively constructed of sheet metal die stampings. The casing 10 85 is preferably made in two sections which are separately shown in Figs. V and VI, and respectively designated 10^a, 10^b. The section 10^a is cup shaped for service as the rotor chamber and has a lateral neck 26 in prolongation of the port 14 adapted for force fitment axially into the section 10^b which affords the annular base flange 15 by which the device is secured. The rotor limiting stop 23 is shown as an integral edge projection of the section 10^a, and the limiting stop 24 as a slight circumferential protuberance of the section 10^b. After assembling, the two component parts of the casing are permanently soldered or welded together at the junction of the neck 26 of part 10^a internally of the part 10^b. 90

The rotor 11 is likewise made in two parts of die stamped sheet metal, these being separately depicted in Figs. VII—VIII the 105 one designated 11^a providing the body 17, and the other identified 11^b, the end 22 of the rotor. The part 11^a is fashioned from a strip of springy sheet metal to the semi-cylindric configuration shown with the ra- 110

dius of curvature slightly larger than that of the rotor chamber of the casing 10 for capacity to engage the chamber wall with snug fluid-tight fit and to hold the rotor 11 frictionally in shifted positions. The inwardly directed radial tongue 27 at one end of part 11^a, enables attachment of the latter coaxially to the discous portion of part 11^b, soldering or welding being here again preferably resorted to for the purpose of permanent connection. The tongue 28, at the opposite end of the part 11^a, is pierced as at 29 in line with the rotor axis for pivotal engagement with a shouldered stud 30 projecting centrally inward from the back wall of the rotor chamber section 10^a of the casing 10; and a convenient means is employed in conjunction with the stud, such for example as a nut 31, to bear against the tongue 28 and retain the rotor 11 in place in the casing 10, said tongue 28 being amply springy to hold the discous portion of part 11^b firmly in frictional contact with the contiguous circumferential edge about the open end of the rotor chamber. If desired, the nut 31 may be permanently secured to the stud 30 by soldering or welding after placement of the rotor 11 in the casing 10. From Fig. VII it will be noted that the segmental cover plate 25 and the grasp lugs 20, 21 of the rotor 11 are formed as integral parts of the member 11^b.

Having thus described my invention, I claim:

- 35 1. A receptacle closure comprising a cylindirc rotor casing having opposed ports and a semi-cylindric rotor for controlling communication through the casing, said rotor having its major body portion free relative to the ends to afford inherent capacity for circumferential flexure to engage the wall of the casing with fluid tightness.
- 40 2. A receptacle closure comprising a tubular rotor casing having opposed ports, a rotor for controlling communication through the casing, an end member attached to the rotor having an arcuate cover plate, and said rotor being of semi-cylindric configuration with the major portion of its body wall inherently springy to afford capacity for circumferential expansion in engaging the wall of the casing with fluid tightness.
- 45 3. A receptacle closure comprising a tubular rotor casing having diametrically opposed ports, a tubular rotor having an opening and a cut-out portion adapted to open and close communication through the casing, an end member attached to the rotor including an integral arcuate cover plate, and said
- 50 40 rotor being of semi-cylindric configuration

with the major portion of its body wall free relative to the ends thereof for expansive engagement with the casing wall to insure fluid tightness.

4. A receptacle closure comprising a hollow tubular rotor casing with aligned diametrical ports, and a rotor to control communication through the casing, said rotor having segmental portions to cover one of the ports interiorly of the casing and the other exteriorly of the casing.

5. A receptacle closure comprising a casing composed of two sheet metal die stamped sections, one of cylindric configuration with aligned diametrical ports and with a lateral neck in prolongation of one of the ports, and the other of annular configuration providing a base flange for attachment of the device and adapted to coaxially receive the neck of the cylindric section, in combination with a similarly composed sheet metal rotor embodying opposed segmental portions adapted to interiorly and exteriorly cover the ports in the cylindric section of the casing.

6. A receptacle closure comprising a hollow tubular rotor casing with aligned upper and lower diametrical ports, in combination with a rotor constructed entirely of die stamped sheet metal embodying a semi-cylindric body portion fitting into the casing to govern the lower port aforesaid and an attached discous end member with an integral lateral segmental plate projection adapted to serve as a cover for the upper casing port.

7. A receptacle closure comprising a hollow tubular rotor casing with aligned upper and lower diametrical ports, in combination with a rotor constructed entirely of die stamped sheet metal embodying a semi-cylindric body portion and an attached discous end member, said body portion fitting into the casing to govern the lower port of the latter and having at opposite ends integral inwardly extending radial arms, one adapted for pivotal connection axially of the casing for retention of the rotor and the other for permanent connection to the end member aforementioned, and said end member having a segmental lateral plate projection adapted to function as a cover for the upper casing port and integral grasp projections to cooperate with stops on the casing in limiting rotor movement.

In testimony whereof, I have hereunto signed my name at Philadelphia, Pennsylvania, this 30th day of January, 1926.

JEAN JACQUES.
